UNITED STATES PATENT OFFICE.

ALBERT A. JACOBI, OF SAGAMORE, MASSACHUSETTS.

BIT-STOCK ATTACHMENT.

Application filed December 17, 1924. Serial No. 756,503.

My invention relates to improvements in bit stocks, and it consists in the combinations, constructions and arrangements herein described and claimed.

- 5 An object of the invention is to provide a bit stock of the type having a sleeve turnably mounted on a shank thereof for clamping the jaws of the bit stock in closed position with an attachment which can be conveniently and easily adjusted on the shank to and from position to frictionally engage with the clamping sleeve, and to then tend to hold the clamping sleeve against turning on the shank when the bit stock is in use.
- 10 15 A further object of the invention is the provision of an attachment of the character described which includes a locking sleeve adapted to be grasped coincidently with the usual clamping sleeve of the bit stock so that the operator of the bit stock can hold the bit stock firmly and manipulate the bit stock accurately.

Other objects and advantages will be apparent from the following description, considered in conjunction with the accompanying drawings, in which:

Figure 1 is a perspective group view showing a bit stock equipped with an attachment embodying the invention, the bit stock shank and the elements which are normally carried thereby being shown separated, and

Figure 2 is a view partly in side elevation and partly in vertical section, showing the elements which are exhibited in Figure 1 assembled with the attachment in frictional engagement with the clamping sleeve of the bit stock.

In the drawings, I show a bit stock having a handle 1, only a portion of which is shown, to which is attached a shank 2. The shank 2 is bifurcated at its free end by a longitudinally extending slot 3 for the reception of portions of the jaws 4. The shank 2 is provided with external screw threads 5 for engaging with the internal screw threads 6 on the inner end portion of a clamping sleeve 7. The clamping sleeve 7 has the bore thereof reduced at its outer end as indicated at 8 for engaging with inclined outer faces of the jaws 4 to force said jaws toward each other, and to position to grip a bit, not shown, when the latter is inserted between the jaws 4 and the clamping sleeve is screwed inwardly on the shank, the jaws normally being urged apart at their outer ends in any suitable known manner, as by means of a

spring such as is partially shown at 9 in Figure 2. The construction described so far is ordinary and forms no part of the invention except in so far as it cooperates with the parts which will now be described. In actual practice, the clamping sleeve 7 is likely to turn on the shank when the bit stock with a bit gripped between the jaws is used in an ordinary manner to an extent sufficient to permit release of the bit from the jaws, which of course retards the progress of the particular work which is being done, and moreover may cause the loss of a bit as when the bit is extended downward through an opening in the wall of a closed chamber or in a like place.

My invention provides means for overcoming this tendency of the clamping sleeve to turn accidentally on the shank. In carrying out the invention, the threads 6 are extended on the shank 2 farther than is usual toward the inner end of the shank and the shank is flattened longitudinally at the inner end of the slot 3 to provide diametrically opposite flat faces on the shank as indicated at 10.

A locking sleeve 11 is provided with a counterbore 12 at the outer end thereof extending for slightly more than half the length of the locking sleeve. The bore of the locking sleeve has screw threads indicated at 13 for engaging with the screw threads of the shank 2 and the counter-bore 12 is adapted to receive the inner end portion of the clamping sleeve 7. A spacing washer 14 is slidable on the shank 2 and is enlarged inwardly at 15 to provide opposite portions having flat faces for engaging with the flat faces 10 on the shank 2 to prevent rotation of the washer 14 on the shank.

From the foregoing description of the various parts of the device, the operation thereof may be readily understood. The washer 14 is placed on the shank 2 within the counter-bore 12 and between the shoulder 16 at the inner end of the counter-bore 12 and the inner end of the clamping sleeve. The clamping sleeve 7 is adjusted on the shank to position to clamp the jaws 4 in gripping relation to a bit or like tool which has been inserted between the jaws. The locking sleeve 11 then is turned on the shank toward the clamping sleeve 7 until the spacing washer 14 has been clamped firmly between the shoulder 16 and the inner end of the clamping sleeve 7 in frictional contact

2
with both the clamping sleeve and the locking sleeve. The locking sleeve 11 and the clamping sleeve 7 then are held as a unit in the one hand of the operator when the handle of the brace is turned by means of the other hand of the operator in the usual manner, and when work is being accomplished in the direction which would tend to cause inward movement of the clamping sleeve 7 on the shank where such movement is possible. The locking sleeve 11 and the spacing washer 14 will function to prevent inward movement of the sleeve 7 on the shank from the position just described, even though the engagement of the bit which is held between the jaws with said jaws and the engagement of the jaws with the outer end of the clamping sleeve would permit such inward movement. In addition, the frictional contact of the washer 14 with the sleeve 7 tends to prevent retrograde or outward movement of the clamping sleeve 7 on the shank, and thus in actual practice is effective to prevent accidental loosening of the grip of the jaws or the bit or like tool which has been held between the jaws. Moreover, the clamping sleeve 7 and the locking sleeve 11 can be gripped as a unit, thus affording an ample hand hold when it is desired to manipulate the shank of the brace by turning it and a tool, such as a screw driver bit which is held between the jaws, about the axis of the shank and tool, as in turning a small screw or a drill of small size, and particularly when "starting" a small screw in the object to which it is to be secured. The outer end

portion of the clamping sleeve ordinarily is knurled or roughened as indicated at 17 and the locking sleeve 11 is knurled or roughened as indicated at 18 so that the clamping sleeve and locking sleeve can be firmly grasped and held against slipping in the hand of an operator.

Obviously, the invention is susceptible of embodiment in forms other than that which has been illustrated in the accompanying drawings, and I therefore consider as my own all such modifications and adaptations thereof as fairly fall within the scope of the appended claim.

50 I claim:—

55 The combination with a bit stock having a shank and a sleeve turnable on the shank, to and from position to hold the jaws of the bit stock closed, said shank having a longitudinally extending flat face at the inner end of said clamping sleeve, of a washer 60 slideable on the shank at the inner end of the clamping sleeve, said washer having an inwardly extending stop portion in sliding contact with said flat face of the shank for holding the washer against rotation on the shank, and a locking sleeve in threaded engagement with the shank for moving said washer longitudinally of the shank to and 65 from position to frictionally engage with the inner end of the said clamping sleeve, said locking sleeve having a counterbore at its outer end for the reception of said washer and the inner end portion of said clamping sleeve.

70 ALBERT A. JACOBI.
